(57) **CLAIM**

We claim the ornamental design for a decanter, as shown and described.

DESCRIPTION

FIG. 1 is a perspective view of a decanter showing our new design;

FIG. 2 is a top plan view of the decanter shown in FIG. 1.

FIG. 3 is a front elevation view of the decanter shown in FIGS. 1 and 2, the rear elevation being a mirror image thereof.

FIG. 4 is a bottom view of the decanter shown in FIGS. 1-3; and,

FIG. 5 is a right side view of the decanter shown in FIGS. 1-4, the left side view being a mirror image thereof.

Broken lines shown in the drawings are environment and do not form part of the claimed design.
